of Delaware

Application August 21, 1941, Serial No. 407,746

8 Claims. (Cl. 62—5)

My invention relates to refrigeration and has for its object to provide an improvement in thermostatic control of refrigeration apparatus, as will appear from the following description taken in conjunction with the accompanying drawings forming a part of this specification, and of which:

Fig. 1 illustrates more or less diagrammatically refrigeration apparatus and a heating system therefor provided with a thermostatic control embodying the invention;

Fig. 2 is a bottom view of the thermostatic control shown in Fig. 1;

Fig. 3 is a sectional view taken at line 3—3 of Fig. 4;

Fig. 4 is a sectional view taken at line 4—4 of Fig. 3; and

Fig. 5 is a sectional view taken at line 5—5 of Fig. 4.

The refrigeration apparatus shown is of a two-pressure absorption type generally as described in application Serial No. 239,762 of A. R. Thomas and P. P. Anderson, Jr., filed November 10, 1938, now Patent No. 2,282,503 granted May 12, 1942. A system of this type operates at low pressures and includes a generator 10, a condenser 11, an evaporator 12, and an absorber 14 which are interconnected in such a manner that the pressure differential in the apparatus is maintained by liquid columns.

The generator 10 includes an outer shell 15 within which are disposed a plurality of vertical riser tubes 16 having the lower ends thereof communicating with a space 17 and the upper ends thereof extending into and above the bottom of a vessel 18. The space 19 within shell 15 and about the tubes 16 forms a steam chamber to which steam is supplied through a conduit 20 from a steam boiler 21.

The boiler 21 is provided with a fire or heating tube 22 into the lower end of which is adapted to project the flame produced by a burner 23. A combustible gas is delivered to burner 23 from a source of supply through a conduit 24 in which is connected an electro-magnetically operated valve 25 connected by conductors 26 and 27 to a suitable source of electrical energy. While only a single heating tube and burner are illustrated, a number of heating tubes and burners may be employed with the upper end of each tube connected to a flue or riser 28. The water in boiler 21 is heated by hot gases passing through the heating tubes 22, thereby producing steam which flows through conduit 20 to generator 10.

The space 19 provides for full length heating of riser tubes 16 with a vent 30 provided at the upper

end of shell 15 through which steam can flow into the atmosphere. Condensate formed in steam chamber 19 is returned to boiler 21 through a conduit 31, a condensate return pump 32 and a conduit 33. The condensate return pump 32 is adapted to be operated by an electric motor 32' mounted thereon, so that return condensate can be raised to a higher level from which it can flow to boiler 21.

10 The heating of riser tubes 16 in generator 10 by the steam causes refrigerant vapor to be expelled from absorbent, such expelled vapor being effective to raise liquid absorbent by gas or vapor-lift action. The expelled vapor passes from the upper ends of the riser tubes into vessel 18, and thence flows through a conduit 34 into condenser 11 in which the expelled vapor is liquefied. The liquid refrigerant formed in condenser 11 flows through a U-tube 35 into the upper part of evaporator 12. The refrigerant evaporates in evaporator 12 with consequent absorption of heat to produce a refrigerating effect which may be utilized to cool an air stream such as, for example, the air caused to flow through a duct 36 which is indicated in dotted lines.

The refrigerant vapor formed in evaporator 12 flows therefrom to an absorber 14 in which the vapor is absorbed into a liquid absorbent, such as lithium chloride solution, for example, which enters the upper part of the absorber through a conduit 37. The absorption liquid enriched in refrigerant is conducted from absorber 14 through conduit 38, a first passage in liquid heat exchanger 39, conduit 40, vessel 41, and conduit 42 into space 17 of generator 10. Refrigerant vapor is expelled out of solution in generator 10 by heating, and the solution is raised by gas or vapor-lift action in riser tubes 16, as explained above.

40 The absorption liquid in vessel 41 is deprived of refrigerant since refrigerant vapor has been expelled therefrom in generator 10. The absorption liquid in vessel 41 flows therefrom through conduit 43, a second passage in liquid heat exchanger 39, and conduit 37 into the upper part of absorber 14. This circulation of absorption liquid results from the raising of liquid in riser tubes 16, whereby such liquid can flow to absorber 14 and return from the latter to the generator by force of gravity. The upper part of vessel 41 and vessel 18 are connected by a conduit 48, so that the pressure in the vessel is equalized with the pressure in the upper part of generator 10 and condenser 11.

The absorber 14 and condenser 11 constitute

heat rejecting parts of the refrigeration apparatus and are cooled by a suitable cooling medium, such as water, for example, which is conducted from a suitable source of supply through a conduit 44 to a bank of tubes 45 within the absorber, whereby heat of absorption is given up to the cooling water. The cooling water is conducted from absorber 14 through a conduit 46 to condenser 11 in which heat of condensation is given up to the cooling water, the cooling water thence leaving the condenser through a conduit 47.

In order to simplify the drawings the parts of the refrigeration apparatus have not been shown in detail, such an illustration of the parts not being necessary for an understanding of this invention. The disclosure in the aforementioned Thomas and Anderson application may be considered as being incorporated in this application and, if desired, reference may be made thereto for a detailed description of the refrigeration apparatus.

In accordance with my invention a thermostatic control device 50 is provided for controlling electro-magnetically operated valve 25 and hence the flow of gas to burner 23. The thermostatic control comprises a switch 51 which is connected in conductor 26, as shown in Fig. 1. The switch 51 is of the normally closed type so that an electrical circuit is normally completed for valve 25 through conductors 26 and 27 for energizing the valve to keep the latter open. However, when an adverse operating condition occurs, as will be explained presently, the contacts of switch 51 are separated to open the electrical circuit for valve 25 whereby the latter closes to shut off flow of gas to burner 23.

The switch 51 is of a well known micro-switch type generally like that described in Patent No. 1,960,020 and having an exterior casing 52 formed of a suitable insulating material, such as Bakelite, for example. The switch contacts within casing 52 are normally closed and are separated by a snap action when an inward movement of approximately .001 inch is imparted to a pin or plunger 53 which passes through an opening in the top of the casing, as shown most clearly in Figs. 3 and 4.

The switch 51 is mounted in the bottom part of a rectangular-shaped shell having a bottom 55, end walls 56, side walls 57, and flanges 58 and 59 extending outwardly from the top edges of the side walls 57. To one of the side walls 57 is secured, as by welding, for example, a flat plate 57' which extends below the bottom 55 and serves as a continuation of the side wall. The switch 51 is secured in position by bolts 60 which pass through openings in the plate 57' and the base of switch 52 and are adapted to receive tightening nuts 61. The bottom 55 of the shell 54 is formed with an opening to receive the switch 51 so that the switch is partly enclosed by the shell, as shown most clearly in Fig. 4. The bottom of switch 51 is provided with terminal connections 62 adapted to be connected to conductor 26, as explained above.

An inverted U-shaped guide member 63 is secured at 64 to the side wall 57 from which the flange 59 extends. The guide member 63 is arranged to receive and hold a part hereinafter referred to as a switch blade, arm or member 65 which is movable lengthwise of casing 54 and passes through a slot in an end wall 56. To the underside of blade 65 is secured a spring clip 66 of the shape shown in Fig. 4, the flat outer end

of such clip being adapted to press and slide over the top of switch 51 and at the same time constantly press and urge blade 65 against the underside of guide member 63.

5 The blade 65 is spring-biased to move toward the right in Figs. 4 and 5. This is accomplished by a coil spring 67 having one end thereof secured to a leg or extension 68 on blade 65 and the opposite end thereof secured to a pin 69 fixed to a side wall 57 of shell 54. When the portion 10 of blade 65 extending outside of shell 54 is pulled outward a sufficient distance against the action of coil spring 67 a lip or tongue 70, which is pressed from one surface of the blade 65, is adapted to contact and engage an edge of guide member 63 to keep the spring clip 66 in the solid line position shown in Fig. 4. Under these conditions switch 51 is normally closed to complete the electrical circuit for valve 25.

When movement is imparted to a pin 71 at the top side of blade 65 so that the lip or tongue 70 is free and clear of guide member 63, the coil spring 67 becomes effective to move the blade 65 toward the right in Figs. 4 and 5 until the right hand end strikes an end wall 56 of shell 54. With the blade 65 in the position shown in Fig. 5, the spring clip 66 is in the dotted line position in Fig. 4, so that the flat outer end thereof of presses against the pin or plunger 53 of switch 30 51. With the spring clip 66 acting against the pin 53 the switch contacts are separated by snap-action movement, as explained above, and the electrical circuit for valve 25 is broken.

Movement is imparted to pin 71 by mechanism 35 including an expansible fluid thermostat including a thermal element 72 of hollow construction formed from a pair of diaphragms having the peripheral edge portions thereof secured together in any suitable manner. The expansible fluid thermostat is charged with a suitable volatile fluid and, in addition to the element 72, includes a pair of thermal bulbs 75 and 76 and a capillary tube 72' connecting the bulbs and the element.

The element 72 is arranged to overlie the upper top of shell 54 with diametrically opposite peripheral edge portions thereof contacting and engaging the flanges 58 and 59. The element 72 is located on the flanges 58 and 59 so that the bottom diaphragm with flexure thereof is capable of acting on pin 71. A ring 73 is provided about the peripheral edge of element 72 and is arranged to be clamped in position by a suitable bracket 74 having openings which are in alignment with similar openings in flanges 58 and 59 and adapted to receive bolts and tightening screws, as indicated at 75' in Figs. 2, 3, and 5, for securing the bracket to the shell 54. The bracket 74 is formed so that pressure is only applied to clamping ring 73 to hold the element 72 in position, the dome or rounded central portion of the bracket being spaced from the bellows, as clearly shown in Figs. 3 and 4.

In the illustrated embodiment of the invention, the expansible fluid thermostat serves as a single control device arranged to shut off flow of gas to burner 23 in the event steam passes from generator chamber 19 through vent 30 into the atmosphere, or the condensate return pump 32 fails to operate. I accomplish this by locating one of the thermal bulbs 75 in the vent 30 and the other bulb 76 in a tube 77 associated with the pump 32 and into which warm condensate overflows from the interior of the pump when the latter becomes inoperative. In the event 70 75 warm condensate flows over the exterior sur-

face of bulb 76 to effect heating of the latter, the pressure of the volatile fluid in the expansible fluid thermostat increases. With sufficient increase in pressure of the volatile fluid in the expansible fluid thermostat, the bottom diaphragm of the element 72 is moved downwardly such a distance that it will act against pin 71. When pin 71 is moved down a sufficient distance so that the tongue 70 is free of the guide member 63, the blade 65 moves toward the right in Fig. 4. When this occurs the spring clip 66 moves to its dotted line position and the contacts of switch 51 are separated to open the circuit for valve 25, in the manner explained above. When the adverse operating condition is corrected and condensate return pump 32 is again operating to return condensate from generator chamber 19 to the boiler 21 and warm condensate no longer overflows into the tube 77, the pressure of the volatile fluid in the expansible fluid thermostat becomes reduced to permit the bottom diaphragm of element 72 to flex upwardly. Under these conditions the outer portion of blade 65 can be pulled outwardly to the position shown in solid lines in Fig. 4, so that the switch 51 is again closed to complete an electrical circuit for the valve 25.

As explained above, it is also desirable to shut off the heat supply to boiler 21 in the event steam flows from generator chamber 19 through vent 30 into the atmosphere. This may occur, for example, when circulation of air past evaporator 12 is not effected and there is loss of load on the latter. By locating the bulb 75 in vent 30 the bulb becomes heated when steam flows through the vent into the atmosphere. With heating of bulb 75 the pressure of the volatile fluid in the expansible fluid thermostat increases to cause the bottom resilient diaphragm of element 72 to move downwardly to act on pin 71, whereby switch 51 is opened to break the electrical circuit for the valve 25, in the manner explained above when bulb 76 becomes heated. When the adverse operating condition is corrected and steam no longer flows through vent 30, the pressure of the volatile fluid in the expansible fluid thermostat decreases so that the bottom diaphragm of the element 72 will move upwardly to the position shown in Fig. 4. When this occurs the outer part of blade 65 can be pulled outward to the position shown in Fig. 4, so that the contacts of switch 51 are again closed to complete the circuit for valve 25.

The thermostatic control 50 is so constructed and arranged that the blade or arm 65 must be manually reset to close switch 51 after an adverse operating condition has been corrected. When the blade 65 is at the extreme righthand position shown in Fig. 5, the portion 78 outside of casing 54 may be painted any suitable color, such as red, and the portion 79 inside the casing may be painted another color, such as black, for example. During normal operation when the blade 65 is in its outermost position, as shown in solid lines in Fig. 4, both the red and black portions 78 and 79 are visible so that it will immediately be apparent that switch 51 is closed and no adverse operating condition has occurred to cause shutting off the heat supply to boiler 21. However, if the element 72 of the expansible fluid thermostat has acted on pin 71 to cause blade 65 to move into casing 54 to cause switch 51 to open, only the red portion 78 of the blade is visible so that it will immediately be apparent that an adverse operating condition has occurred to shut off the heat supply to the boiler 21. Thus,

even though switch 51 is of the micro-switch type operable when only a movement of approximately .001 inch is imparted to pin or plunger 53, the blade or arm 65 serves as a part having a relatively large movement to show immediately upon visual inspection whether or not switch 51 is closed or open depending upon the position of blade 65.

In addition to the control described, a normal control is usually provided for controlling the fuel supply to the burner 23 or a plurality of such burners, so that the rate at which steam is supplied to generator steam chamber 19 can be controlled. The normal control is generally operative responsive to a temperature condition affected by the cooling element and may be of the character described in my application Serial No. 406,777 filed August 14, 1941, in which sequential control of a plurality of burners is effected.

The normal control may include switches which are also connected in the circuit of the valve 25 so that, when an adverse operating condition occurs which causes flow of steam through the vent 30 or overflow of warm condensate into tube 77, the control described above will open the circuit of the solenoid valve to shut off flow of fuel to the burner or burners. When the adverse operating condition is corrected and steam no longer flows through the vent 30 or warm condensate does not overflow into tube 77, the switch 51 can be manually closed to complete the circuit for the valve 25 so that the above-described normal control of the burner 23 may be resumed to control the rate at which heat is supplied to boiler 21.

Although a single embodiment of the invention has been shown and described, it will be apparent that modifications and changes can readily be made without departing from the spirit and scope of the invention, as pointed out in the following claims.

What is claimed is:

1. In refrigeration apparatus, a micro-switch provided with an operating pin having a reciprocatory movement, said switch being operable with movement imparted to said pin in the neighborhood of .001 inch, an expansible fluid thermostat responsive to a temperature condition affected by said apparatus and including a hollow element having a movable wall member, mechanism operatively associating said pin and said wall member, said mechanism including a blade having reciprocatory movement in a lengthwise direction through a distance considerably greater than .001 inch and serving as an indicator to indicate the condition of said switch, said blade also being movable in a second direction transverse to its length, and said mechanism being so constructed and arranged that said blade is manually movable in a lengthwise direction to a first position and biased to move to another position when movement is imparted thereto in the second direction by said movable wall member, the movement of said blade to said other position imparting movement to said pin to actuate said micro-switch.

2. In refrigeration apparatus, a control device including: an electric switch, structure including a member and a thermostatic element responsive to a temperature condition affected by said apparatus for operating said switch, said member having reciprocatory movement and also being movable transverse to the direction of said reciprocatory movement, and said structure

being so constructed and arranged that said member is manually movable in said direction to a first position and biased to move to another position when said transverse movement is imparted thereto by said thermostatic element, the movement of said member in said direction to said other position actuating said switch, said member being of such size and having sufficient movement in said direction to indicate readily the condition of said switch.

3. In refrigeration apparatus, a control device including: a switch, structure including a blade and a thermostatic element responsive to a condition affected by said apparatus for operating said switch, said blade having lengthwise reciprocatory movement between first and second positions and also having movement transverse to the direction of said reciprocatory movement, said blade being of such size and having sufficient lengthwise movement to indicate readily the condition of said switch, resilient means to urge said blade to said first position, a catch for holding said blade in said second position against the action of said resilient means, and said structure being so constructed and arranged that said transverse movement is imparted to said blade by said thermostatic element to release said blade from said catch to allow said blade to move from said first position to said second position, the movement of said blade to said second position actuating said switch.

4. In apparatus operated by heat and having a part provided with a chamber; a steam boiler, said chamber being connected to receive steam from said boiler, means including a pump to return to said boiler condensate formed in said chamber due to condensation of steam supplied thereto, structure including valve means, and a device responsive to a temperature condition affected by warm condensate when said pump fails to operate for operating said valve means, said device including: an electric switch associated with said valve means, structure including a thermostatic element for operating said switch, and a part manually movable to a first position and serving as an indicator for indicating the position of said switch, said part being biased to move from said first position to a second position when said switch is actuated by said thermostatic element.

5. In a refrigeration system operated by heat and having a heat receiving part provided with a chamber, said chamber being connected to receive steam from a source of supply and having a vent to atmosphere; structure including an electric circuit, electro-magnetically operated valve means in said circuit, and a device responsive to a temperature condition affected by flow of steam through said vent into the atmosphere for operating said valve means, said device including a micro-switch adapted to be connected in said circuit, a thermostatic element, and mechanism operatively associating said element and said switch, said switch being operable with slight movement imparted thereto, and said

mechanism including a part movable through a distance considerably greater than that necessary to operate said switch, said part serving as an indicator to indicate the condition of said switch.

6. In refrigeration apparatus having a heat receiving part, a steam boiler, said part being arranged to receive steam from said boiler, and means including a pump to return to said boiler condensate formed at said part due to condensation of steam supplied thereto; structure including an electric circuit, electro-magnetically operated valve means in said circuit, and a device for operating said valve means responsive to a temperature condition affected by warm condensate when said pump fails to operate, said device including a micro-switch adapted to be connected in said circuit, a thermostatic element, and mechanism operatively associating said element and said switch, said switch being operable with slight movement imparted thereto, and said mechanism including a part movable, through a distance considerably greater than that necessary to operate said switch, said part serving as an indicator to indicate the condition of said switch.

7. In apparatus operated by heat and having a part provided with a chamber, said chamber being connected to receive steam supplied thereto from a source of supply; a vent for venting excess steam from said chamber to the atmosphere, structure including valve means, and a device operative responsive to change in a temperature condition affected by flow of steam from said vent into the atmosphere for operating said valve means; said device including an electric switch associated with said valve means, structure including a thermostatic element for operating said switch, and a part movable to a first position and serving as an indicator for indicating the condition of said switch, said part being biased to move from said first position to a second position when said switch is actuated by said thermostatic element.

8. In apparatus of the character described, a control device including: a casing, a micro-switch carried by said casing, structure comprising a thermostatic element having a movable part disposed within said casing and an indicator operatively associated with said structure and having a part projecting outside said casing for indicating the condition of said switch, said indicator having reciprocatory movement between two positions and also being movable transverse to the direction of said reciprocatory movement, said structure being so constructed and arranged that said indicator is held in one of said positions and released from said one position and moved to the second of said positions when moved transverse to said direction by said movable part, said indicator being arranged to actuate said switch when moved from said first to said second position.

SVEN W. E. ANDERSSON.
